UNITED STATES PATENT OFFICE

150,517

DESIGN FOR A CAMERA

Seton I. Rochwite, Wauwatosa, Wis., assignor to
David White Company, Milwaukee, Wis.

Application January 24, 1947, Serial No. 136,401

Term of patent 14 years

(CL. D61—1)

To all whom it may concern:

Be it known that I, Seton I. Rochwite, a citizen of the United States, residing in Wauwatosa, in the county of Milwaukee and State of Wisconsin, have invented a new, original, and ornamental Design for Cameras, of which the following is a specification, reference being had to the accompanying drawing, forming a part thereof.

In the drawing:

Fig. 1 is a front perspective view of a camera, showing my new design with the lens cover in a closed position.

Figure 2 is a perspective rear view of the camera.

Figure 3 is a front view of the camera with the lens cover in an open position.

Figure 4 is a top view of the camera with the lens cover closed.

Figure 5 is an end view of the camera with the lens cover closed, and

Fig. 6 is a view of the opposite end of the camera shown in Fig. 5 with the lens cover open

I claim:

The ornamental design for a camera, as shown.
SETON I. ROCHWITE.
